[57] CLAIM

The ornamental design for a canopy for a juvenile playard, as shown and described.

DESCRIPTION

FIG. 1 is a perspective view of a canopy for a juvenile playard with a front screen partially open;

FIG. 2 is a front view of the canopy for a juvenile playard with a front screen closed;

FIG. 3 is a left side view of the canopy for a juvenile playard;

FIG. 4 is a back view of the canopy for a juvenile playard; and,

FIG. 5 is a top view of the canopy for a juvenile playard.

The broken lines are for environmental purposes only and form no part of the claimed design.

The right side view is a mirror image of the left side shown in FIG. 3.

The bottom of the article is not part of the claimed design.
